UNITED STATES PATENT OFFICE.

PAUL S. MILLICE, OF MIAMISBURG, OHIO, ASSIGNOR TO FIRE-PROOF FURNITURE AND CONSTRUCTION COMPANY, OF NEW YORK, N. Y., A CORPORATION OF NEW YORK.

FILING DEVICE.

1,032,491.

Specification of Letters Patent. Patented July 16, 1912.

Application filed November 18, 1911. Serial No. 661,086.

To all whom it may concern:

Be it known that I, PAUL S. MILLICE, a citizen of the United States, residing at Miamisburg, in the county of Montgomery and State of Ohio, have invented certain new and useful Improvements in Filing Devices, of which the following is a specification.

My invention relates to filing devices, especially to means for supporting the papers or articles filed, and comprises a follower and novel means for guiding and locating the follower, and arranging the same with relation to the drawer and the casing in which the same is contained, and further comprises novel locking means for the follower.

It is the object of my invention further to provide a follower which occupies little space longitudinally of the drawer or container, and novel locating means therefor, which are quick and firm in their action and of such construction as to provide large filing space in the drawer or container, and the invention will be further readily understood from the following description and claims, and from the drawings, in which latter:

Figure 1 is a plan view of my improved device shown in connection with so much of a filing cabinet as is necessary to illustrate my invention, the filing cabinet being shown in horizontal section and the middle portion thereof being broken away for better illustration of parts. Fig. 2 is a rear view of my improved device, the drawer being shown in section on the line 2—2 of Fig. 1 and the clamping lever being shown in unclamped position in full lines and in clamped position in dotted lines. Fig. 3 is a horizontal section of the same taken on the line 3—3 of Fig. 2, showing the device in unclamped relation. Fig. 4 is a similar view of the same, with the parts shown in clamped relation. Fig. 5 is a cross-section on the line 5—5 of Fig. 3. Fig. 6 is a similar view taken on the line 6—6 of Fig. 4. Fig. 7 is a section of my improved device taken on the line 7—7 of Fig. 2. Fig. 8 is a rear elevation of the same showing one of the clamping-pieces removed. Fig. 9 is a perspective view of one of the clamping-pieces. Fig. 10 is a cross-sectional detail, taken on a line corresponding to the line 10—10 of Fig. 8, showing the rocking connection be-

tween the mating angle-pieces. Fig. 11 is a detail showing a portion of the rear wall of the drawer and the wing-receiving opening therein; and, Fig. 12 is a detail showing an inside side elevation of the front portion 60 of the drawer and the wing-receiving pocket therein.

11 represents the casing and 12 a drawer in the casing, movable back and forth in suitable runways 13. The rear wall 14 of 65 the drawer is preferably spaced from the rear wall 15 of the casing or cabinet, when the drawer is closed, as indicated by the space 16.

17 is a follower movable lengthwise of the 70 drawer or container which is arranged to receive the letters, papers, documents or other articles to be filed. The follower is arranged to be placed at suitable points 75 lengthwise of the drawer for suitably supporting or compressing the articles between it and the front 18 of the drawer, the position of the follower being arranged to be changed upon insertion or removal of articles for supplying additional space between 80 the follower and the front of the drawer, and the construction of the device may be such that the follower is adapted to be moved back when the articles in the drawer are being referred to and moved forwardly 85 for compressing the articles when the same are no longer in use.

I have shown my improved device in connection with a metal filing cabinet, and I 90 preferably construct the same of metal.

The drawer is provided with a guide, preferably at each side thereof, shown in the form of a channel 21 in each of the sides 22 of the drawer, the walls of the channel being bent outwardly from the inner face 23. 95 of the drawer for locating said channels outside said inner walls, so as to permit the location of the positioning means for the follower outside of the filing space, indicated at 24, in the drawer. The channel preferably comprises an outer wall 25 and an inner wall 26, the latter shown as bent downwardly from the upper edge 27 of the side of the drawer. The channel forms a guideway and by it, in the preferred form 100 of my invention, one of the coacting locking members for the follower is formed. This locking member extends longitudinally of the drawer. The locking member coacting therewith is located on the follower, and is 110

shown as a member which normally extends parallel with the guide therefor on the drawer and has tilting connection with the follower for tilting the same out of normal parallelism with said guide for clamping the same to said guide and thereby positioning the follower. In the preferred form of my invention there is a pair of these locking members on the follower for each of the guides, the same being arranged on angle-pieces which I shall now describe, the angle-pieces being preferably duplicates of each other, and I shall refer to them and the parts thereon by similar reference numerals.

15 31 is an angle-piece which has a wing 32 arranged to be received in the guideway and a wing 33 extending crosswise of the drawer. The wing 33 is provided with a lug 34 at one of its side-edges and a lug 35 at its inner end. The other side-edge of the wing has a slot 36 therein. The face from which said lugs project may also be provided with a recess 37. The end-lug 35 is adjacent one of the side-edges of said wing for forming 20 a rabbet 38 at the other of said side-edges.

25 39 and 40 are holes in the wing 33, and 41 is a projection projecting from said wing in the direction of the lugs 34, 35, this projection being at one side of the hole 39, an indentation 42 being at the other side of said hole. The lugs and projection are so arranged on the angle-piece that when the faces from which they project are presented toward each other, in assembling a pair of 30 said angle-pieces, the side-lug on one of said angle-pieces will be received in the side-slot of the mating angle-piece, and the end-lugs be at opposite edges of said laterally projecting wings, these end-lugs having a 35 space 50 therebetween through which the shank 51 of a rocker-member 52 is received, the said rocker-member having a cam-portion 53 thereon received in the mating recesses 37 in the adjacent faces of said pair 40 of wings. The projection 41 on each of said angle-pieces is received in the indentation 42 on the other of said angle-pieces. These angle-pieces are arranged in pairs, one of these pairs being arranged at each end of 45 the follower, with the longitudinal wings extending in opposite directions and received in the guideways at the respective sides of the drawer. The wing which is adjacent to the follower is secured to the follower as by 50 a rivet 54 or other suitable connecting member received through the hole 40 therein. The angle-pieces of each pair are rockingly associated as by means of a bolt 55 and nut 49 firmly held thereon, or other suitable connecting member, received through the holes 55 55, the projections between the adjacent faces permitting rocking of one of the said angle-pieces upon the other.

60 The rocker-member 52 is preferably made of a metal rod, the middle portion of which

is bent outwardly for forming a handle 56 and the ends of which are provided with an angular bend for forming the cam-portions 53. The handle is provided with a bend 57 which, when the parts are in locked relation, 70 is received under the rearwardly extending upper portion 58 of the follower, in which relation the outer bent ends 53 of the rocker-member project at right angles to the plane of said follower, or pass a line at right angles thereto, for maintaining the parts in locked relation. The parts are easily placed in unlocked relation by pressing down the handle, whereby the same assumes a position at substantial right angles to the plane of 80 the follower and the said bent ends assume a position substantially parallel to said plane. The wings projecting transverse to said follower normally extend substantially parallel to the longitudinal projection of the 85 guide or locking member, which extends longitudinally of the drawer. If now, the said wings are rocked or tilted, they will assume positions out of said parallelisms and thereby crowd upon or clamp said guide 90 or longitudinal locking member and thereby hold the follower in the position at which it may at the time be located lengthwise of the drawer.

The relation of the parts in the present 95 exemplification of my invention is best illustrated by comparing Figs. 3 and 5, in which the unlocked relation of the parts is shown, and Figs. 4 and 6, in which the locked relation of the parts is shown, the wings in 100 the latter figures being shown clamped between the outer wall 25 and the inner wall 26 of the guideway. The locking wings are shown extending to the front and rear of the follower at the sides of the filing space, 105 leaving the filing space clear of obstruction, but locating the forward wings in a transverse plane coincident with the transverse plane, when extended, of the filing space. For permitting maximum employment of 110 the filing space, the rearwardly extending wings are arranged to be received through openings 59 in the rear wall 14 of the drawer into the space 16, and the front wings are arranged to be received in pockets 115 60 formed by inclined inclosing side walls 61 forming extensions of the sides 22 of the drawer.

In the present exemplification of my invention, the wings and guideways form a 120 slide-support for the follower and are arranged to be shifted into locking relation in said guideways for lockingly positioning the follower at desired points longitudinally of the drawer. As hereinbefore 125 stated, the parts are preferably made of metal, the said guides and follower being formed of resilient sheet-metal which in practice is slightly resiliently distorted when the parts are placed in locking rela- 130

tion, the resilience of said sheet-metal parts causing said locking parts to spring into normal unlocked relation when the handle 56 has been sufficiently swung for turning 5 the cam a distance sufficient to bring its high point back substantially out of a right line between the rocking axis of said rocking-member and its point of locking contact with said follower.

10 The lugs 34, 35, are sufficiently long to maintain the adjacent wings in proper relation irrespective of their degree of separation and for maintaining the shanks of the rocking-member between said end-lugs 15 throughout the shifting movements of the parts. The projections 41 being received in the indentations 42 aid in holding the opposed wings in alinement.

The wing 33 preferably connects with the 20 wing 32 by means of a neck 43 having a mouth 44 at either side thereof for the reception of the flange 26, the lower wall of channel 21 being devoid of obstruction for permitting ready insertion of the wing 32.

25 Having thus fully described my invention, what I claim as new and desire to secure by Letters Patent, is:

1. In a filing device, the combination of a container having a guide, a follower, a 30 pair of angle-pieces on said follower having wings received by said guide normally substantially parallel, and means for shifting the said wings out of said parallelism for clamping said follower to said guide.

35 2. In a filing device, the combination of a container having a guide, a follower, a pair of angle-pieces on said follower having wings received by said guide normally substantially parallel and other wings 40 alongside said follower, and means for causing relative shifting between said last-named wings whereby said first-named wings are shifted out of said parallelism for clamping said follower to said guide.

45 3. In a filing device, the combination of a container having a guide, a follower, a pair of angle-pieces on said follower having wings in substantial parallelism received by said guide and other wings alongside said follower, and separating means between said last-named wings for causing relative shifting of said first-named wings and clamping thereof to said guide.

55 4. In a filing device, the combination of a container having a guideway, a follower, a pair of guide-pieces on said follower having articulation between them and provided with wings extending in reverse directions in said guideway, and means for causing 60 tilting movement between said guide-pieces for causing binding of the wings thereof in said guideway.

5. In a filing device, the combination of a container having a locking member extending longitudinally thereof, a follower,

a pair of angle-pieces having wings substantially parallel with said follower and wings extending in reverse directions substantially longitudinal of said locking member, said angle-pieces articulated together, 70 and a cam-piece received between said first-named wings for changing the longitudinal arrangement of said second-named wings, for the purpose specified.

6. In a filing device, the combination of 75 a container having a locking member, a follower, oppositely extending locking wings on said follower for coacting with said locking member, and means for changing the direction of extension of said wings for clamping the same to said locking member.

7. A positioning means for the follower of a filing device comprising mating angle-pieces having wings extending side by side and other wings arranged lengthwise of 85 each other and at an angle to said first-named wings, and means for causing tilting between said angle-pieces for changing the relation of one of said sets of wings to a coacting positioning part therefor.

8. In a filing device, the combination of 90 a casing, a drawer therefor having a guideway therein, a follower, and a clamping wing on said follower in said guideway, said drawer having an opening in the back 95 thereof in line with said clamping wing for receiving the same, substantially for the purpose described.

9. A positioning means for the follower of a filing device embracing a rockable 100 member, and a pair of parts having to and fro movement between them, said pair of parts provided with side-guides for guiding said separating movement and with end-guides for positioning said rockable member, substantially as described.

10. A positioning means for the follower of a filing device embracing a rockable member, and a pair of parts having to and fro movement between them, said pair of 110 parts provided with side-guides for guiding said separating movement and with end-guides for positioning said rockable member, said rockable member having a cam-portion between said pair of parts.

11. A positioning means for the follower of a filing device embracing a rockable member, and a pair of parts having to and fro movement between them, said pair of parts provided with a pivot-portion between 120 them, with side-guides for guiding said to and fro movement and with end-guides for positioning said rockable member, said rockable member having a cam-portion between said pair of parts, substantially as described.

12. A positioning means for the follower of a filing device embracing a pair of parts each having thereon a side-guide, an end-guide and a guiding wing arranged in oppo- 130

site relations when the parts of said pair of parts are placed in mating relation.

13. A positioning means for the follower of a filing device embracing a pair of parts each having thereon a side-guide, an end-guide, a pivot-projection, and a guiding wing arranged in opposite relation when the parts of said pair of parts are placed in mating relation, and a rocker-member arranged to be received between said parts.

14. In a filing device, the combination of a casing, a drawer received therein, said drawer provided with a guideway, the back of said drawer provided with an opening in line with said guideway, and the front of said drawer provided with an inclined inclosing side-wall received over said guideway, a follower in said drawer, guiding and positioning means for said follower embracing guide-parts having wings extending in opposite directions from said follower lengthwise of said guideway and arranged to be respectively received through said opening and under said inclosing side-wall, and means for causing said wings to bind in said guideway.

15. In a filing device, the combination of a drawer, a follower therein, said drawer having a locking member at each of the sides thereof, a coacting locking member for each of said first-named locking members having a wing extending longitudinally of one of said first-named locking members and tilting connection with said follower, and means for tilting said second-named locking members.

16. In a filing device, the combination of a drawer, a follower therein, said drawer having a locking member at each of the sides thereof, a coacting locking member for each of said first-named locking members having a wing extending longitudinally of one of said first-named locking members and tilting connection with said follower, and a rocker-member having connection with said second-named locking members for tilting the same.

17. In a filing device, the combination of a drawer, a follower therein, said drawer having a locking member extending longitudinally thereof at each of the sides thereof, a pair of coacting locking members for each of said first-named locking members, means for tiltingly connecting the coacting locking members of said respective pairs, means for securing one of the locking members of each pair to said follower, the locking members of said respective pairs having oppositely

extending wings extending lengthwise of said respective first-named locking members, and means for causing tipping movement between the locking members of said respective pairs, for the purpose described.

18. In a filing device, the combination of a drawer provided with a metal guideway, a follower, oppositely extending wings on said follower received longitudinally in said guideway, and means for changing the relative longitudinal arrangement of said wings for clamping said follower to said drawer.

19. In a filing device, the combination of a drawer provided with a metal guideway at each side thereof, a follower, a pair of oppositely extending wings on said follower received longitudinally in each of said guideways, and a rocker-member having connection with each of said pairs of wings for changing their longitudinal arrangement in said guideways and clamping said follower to said drawer.

20. Duplicate angle-pieces for the clamping means of a follower in a filing device, each having a guide-wing and a wing arranged for having connection with said follower and having extending from one of its faces a wing-guiding side-lug, a cam-guiding end-lug, and a pivot-projection, so arranged that when said faces of a pair of said angle-pieces are placed opposite each other the said lugs and pivot-projections will be at opposite sides of opposite ones of said faces and act in opposition to each other.

21. Duplicate angle-pieces for the clamping means of a follower in a filing device, each having a locking-wing and a wing having a wing-guiding side-lug, a cam-guiding end-lug and a pivot-projection from one of its faces, extending and so arranged that when said last-named faces of a pair of said angle-pieces are placed opposite each other the said lugs and pivot-projections will be on opposite sides of opposite ones of said faces and act in opposition to each other, each of said last-named wings being provided with a hole for a securing connection to said follower and with a hole for an articulating connection between said pair of angle-pieces.

In testimony whereof, I have hereunto signed my name in the presence of two subscribing witnesses.

PAUL S. MILLICE.
